APPAREL GARMENT

Waldemar Kops, New York, N. Y., assignor to
 Kops Brothers, Inc., New York, N. Y., a corporation of New York

Application April 9, 1935, Serial No. 15,385

1 Claim.

(Cl. 2—27)

This invention relates to a garment of wearing apparel and more particularly to a garment in the nature of a corset which is adapted to surround and confine the body of a wearer and extend from above the bust line to below the hips.

An object of this invention is to provide a garment in which there is a belt having in conjunction therewith an abdominal support with a certain amount of vertical adjustability, so that a single garment may be readily adapted for use by persons having different requirements as to the location of the lower end of the support. This does away with the necessity of manufacturing garments with belts of a number of different widths in order to adequately fit wearers having abdomens depending to different extents. By my invention, providing a vertically stretchable abdominal support, a corset shop is enabled to satisfy the varied demands of its customers without carrying a large stock. One difficulty heretofore in garments equipped with abdominal supports has been that the belt portion when lifting the abdomen and pushing the flesh upwardly and outwardly has caused what is known as "pitch", that is, the belt instead of remaining in a vertical position has had a tendency to slant in close to the body at its lowest edge and pull away from the body at its upper edge, thus causing a bulge adjacent the diaphragm of the wearer.

By making the abdominal support stretchable vertically, a garment is provided which is adapted to lift and maintain the abdominal organs in their correct and natural position without creating this "pitch". The support has been rendered more efficient and effective in other respects also and affords greater comfort to the wearer. Further objects of the invention will be apparent from the detailed description of one embodiment of my invention in conjunction with the accompanying drawings in which—

Figure 1 is a perspective view of the garment being worn, but with the outer or body member partly thrown back to show the belt in wearing position.

Figure 2 is a front elevation on a larger scale with a portion of the outer member broken away to show the belt.

Figure 3 is a plan view of the garment opened up and viewed from the inner side thereof.

Figure 4 is a sectional view on the line 4—4 of Figure 3, and

Figure 5 is a sectional view on the line 5—5 of Figure 2.

The garment of my invention in its preferred embodiment, which is illustrated, comprises a

body member 2 which may be detachably fastened along the left side by any suitable means so that it surrounds the body of the wearer. This body member is made up of front section 3 and back section 4 in conjunction with side sections 5 and 6. The front section preferably extends from above the bust line to below the hips and is made up of three main portions including lateral portions 7 and 8, and a central portion 9. These three sections are longitudinal with respect to the wearer's body and joined by suitably stitched reinforcing seams at 10 and 11. This may, of course, all be one piece of cloth, if desired, and simply reinforced by binding tape or other suitable means. The lateral section 7 is preferably curved at its outer edge 12 so as to conform more readily to the contour of the body and is provided with suitable fastening means. Central portion 9 is preferably reinforced by a lining member 9' extending from the line 13 to 20 the upwardly curved line 14 and held at its vertical edges by the stitching 10 and 11 joining the lateral sections to the central section. This lining member may be stitched to the main garment at its lower edge, but is preferably left free to 25 prevent the garment from wrinkling. The central section may also be supplied with an elastic inverted V-shaped insert or gore, as at 15, to assist in allowing the garment to conform to the body and to provide for extra stretching when 30 the body is in a bent position, as in sitting down. The whole front section is cut away along the lines 16 and 17 to allow for the incorporation of brassière elements in the form of pieces of suitable material 18 and 19, joined to the front section 3 as by stitching down from the top along the lines 20, 21 to points near the juncture of lateral sections 7 and 8 with central section 9 and thence upwardly and outwardly along the 35 lines 22 and 23.

The back section 4 is made up of three longitudinal sections 24, 25 and 26 connected by suitable reinforcing members 27 and 28 and the whole assembly tapers slightly inwardly toward 45 the top. The reinforcing members may provide pockets for stays 29 and 30, if desired. Additional reinforcement is desirable in the lateral sections 24 and 25 and preferably consists of the lining pieces 31 and 32 reinforced with strips 33 and 34 by suitable stitching providing pockets for stays 35 and 36. These lining pieces are preferably not stitched to the back at 37 and 38. A similar lining piece 39 is provided at the bottom of the center sections 26 and is stitched into 50 55

the side seams 27 and 38, across the bottom, and across its top along the seam 40.

The front portion and the back portion are joined by the inwardly tapered side section 5 attached at the reinforced seams 41 and 42. Provision is made at the latter seam for stay 43 extending from the top to a point slightly below the waist line. In the lower portion of this side section there is inserted a V-shaped piece 44 of elastic material. Side section 6 is joined to the back section at its other side by a reinforcing strip 45, which provides a pocket for a stay similar to stay 43. Another elastic insert 48 may be used here similar to insert 44. The other side 15 of this side section is curved at the edge 47 symmetrically with edge 12 and has fastening means adapted to cooperate therewith.

The abdominal support is associated with the main portion of the garment in such a way that it 20 serves to lift and pull back the abdomen, providing an overlying portion to secure a straight line and the whole cooperating with the back section 26 of the main garment which functions as a buttocks retainer.

25 The abdominal support is made up of a belt, which is connected to the outer garment by the seams 42 and 45. Three major sections make up the belt and consist of a front section 49, permanently connected to a side section 50 by means of the elastic strip 51, and to a side section 52 which is joined to the other side of the back portion of the main garment at the seam 45. This latter side section tapers inwardly from bottom to top and is preferably cut at an angle along the lines 53 and 54 to obtain a better fitting. The bottom edge 53 is in a position to follow the line of the groin of the wearer, thus affording the best support. A reinforcing strip is suitably stitched in place for additional strength at the 40 seam 55 joining the separate portions of section 52 and an elastic strip 56 is joined to the section 52 at a reinforced seam 57 which provides a pocket for a short stay 58 near its top.

Suitable fastening means such as eyes 61 are 45 fixed into the binding at the outer edge of elastic strip 56 and are shielded from the body of the wearer by means of an overlapping strip 62 of some soft material, such as flannel, which is stitched to the elastic along a seam 63. Side section 50 is similar to section 52 and is reinforced by a strip 64. It is, also, preferably cut at an angle along its top 65 and bottom 66. However, if it should be desired, both the sections 50 and 52 may be substantially rectangular in shape, 50 without an attempt to conform to the contour of the body, or they may be cut on any other suitable angle. Reinforcing seams 67 and 68, joining the elastic strip 51 to the front section 49 and side section 50 are preferably stitched to provide short pockets in their upper portions for the stays 69 and 70. Front section 49 may be substantially rectangular in shape but is preferably tapered slightly inwardly, curved at its top edge 71, and somewhat cut away at its bottom edge 72. Relatively wide longitudinal reinforcing strips 73, 74, and 75 are stitched into this front section in a slightly fan-shaped arrangement and provide pockets for stays which are correspondingly wider than usual. A substantially keystone shaped diaphragm supporting lining piece 76 is sewed into the front section 49 by the stitching along the upper edge 71, down the side seams 68 and 77 and down the center by seams 78 and 79. This lining member 70 is simply bound at the edges 80 and 81 but not 75

fastened to the front section 49. The stitching at 78 and 79 may be entirely eliminated or stitching may be provided in addition thereto or in lieu thereof along the seams of the reinforcing strips 73 and 75.

At the free edges of the front section suitable fastening means, such as hooks 82, are attached to the binding adapted to cooperate with eyes 61 to fasten this belt around the wearer. Immediately below the diaphragm support and 1 fastened thereto by suitable stitching 84 is an abdominal supporting member 83, preferably made of elastic material which stretches only in a vertical direction, and shaped to conform to the contour of the abdomen as by means of the 1 seam or dart 83'. In the claims this shape of the vertically stretching abdominal support is referred to as "slightly pocketed". Of course, it will be apparent that this member may also if desired be made of elastic material having a two-way stretch as long as it can be stretched vertically. This member is preferably joined to the girdle proper only at the aforementioned seam 84 and is thus supported from substantially only one point. By the use of one-way or two-way stretch elastic material, with a capability of stretching at least vertically, this member is adapted to be pulled down well under the abdomen to lift it when released. It is connected at one of its sides to an elastic member 85 by suitable stitching, as the seam 86, which member is in turn attached to side section 50 at 87. Thus, the side support 85 of the sling extends around the body in a slightly downwardly direction. The abdominal support 83 is provided at its opposite edge with eyes 88 attached to the binding thereof and adapted to cooperate with hooks 89 to fasten the sling so formed in position. A piece of suitable soft material 90 serves to shield the body from the fasteners and is sewed to the support at the seam 91. An elastic member 92, similar to member 85, is stitched into seam 57 along the line 93 and carries the hooks 89, thereby cooperating in pulling the support 83 back into place.

As mentioned above, in the preferred embodiment of my invention, the elastic of the abdominal support 83 stretches only in a vertical position, while the elastic of supporting sections 85 and 92 stretch only in a substantially horizontal direction, thus providing an assembly which simultaneously lifts the abdomen and pulls it back into place, while by cooperation with the back member 26 through side sections 50 and 52 it functions as a buttocks retainer. The main portion of the girdle 49 overlies the sling, provides additional support, and smooths out any bulges which may be produced by the sling, being only loosely attached to this member.

The whole garment may be supported from the shoulders by means of straps 94 and 95 of elastic or other suitable material. These straps are joined to the back portion 26 at the seams 96 and 97 and to the top of the brassière elements at the points 98 and 99. If desired, cross straps 100 and 101 may be stitched in to distribute the pull on the said brassière members. Suitable adjustable hose supporters may also be supplied, such as the depending members 102 and 103 at the back of the garment. In the front I prefer to attach one end of the elastic straps 104 and 105 to the girdle at the points 106 and 107, while the other end thereof is attached to the main body member 2 by the seams 108 and 109. The

hose supporters, themselves, hang from these straps on the freely sliding members 110 and 111. As will now be understood the garment comprises chiefly three substantially independent layers across the front of the body, all connected to the back portion of the garment by elastic means. Of these three layers the inner one, or sling supporter, is substantially all of elastic material. The main portion of the abdominal belt overlies and covers this sling supporter, smoothing out any bulges that may be caused thereby. The outer portion of the garment overlies and covers the whole belt assembly and provides a smooth surface on which outer garments may rest. Also, if one portion of the garment should be pulled, or come out of place in any way, it does not materially affect the position of the other portions of the garment, which are substantially independent thereof. The sling support can be stretched and pulled down to any desired place on the body when being put in position, and when released will automatically lift the abdominal walls to their correct position. The side elastic bands of the sling supporter, in addition to 25 acting in the lifting of the abdomen insures correct positioning along the groin line of the wearer.

The fastening means may, of course, be all located on the right side, or arranged in any other suitable manner.

As described the garment has three sets of fasteners. These may be condensed, for example, into two sets by stitching the elastic member 92 to the central support 83, stitching the free edge of elastic strip 56 to the free edge of the belt or 35 central section 49, and providing simply a single row of fasteners along the edge of member 52, to replace the seam 57, adapted to cooperate with other fasteners on the then free edges of elastic strips 56 and 92. It will be understood that these 40 free edges of these strips will then be joined to-

gether by stitching to facilitate fastening by the single set of fasteners.

Other modifications may be made. The sections 83, 85 and 92 might be a unitary piece cut out of two way stretch elastic material or these three sections together with supporting member 76 might be similarly a single piece of two way stretch elastic fabric. On the other hand sections 76 and 83 could be a unitary member of either vertically stretchable one-way elastic or 10 two-way stretch material. In any of these modifications, of course, the sling portion of the main belt may be simply suspended from the top edge 71 or it may in addition be tacked to the main belt at 84, or the manner of attachment which 15 has previously been described may be followed.

The terms and expressions which I have employed are used as terms of description and not of limitation, and I have no intention, in the use of such terms and expressions of excluding any 20 equivalents of the features shown and described or portions thereof, but recognize that various modifications are possible within the scope of the invention claimed.

What I claim is:

In an apparel garment a body encircling member, and an inner belt member within said body encircling member comprising an elastic abdominal support made up of a central elastic member arranged to exert a vertical pull to lift the abdomen, elastic side members connected with said central member and arranged to exert a transverse tension thereon to hold said central member in place, and a member of elastic and inelastic material overlying said central and side members, 30 at least a portion of said central elastic member being adjustable vertically independently of said overlying member.

WALDEMAR KOPS. 40
